(57) **CLAIM**

The ornamental design for a tape dispenser, as shown and described.

DESCRIPTION

FIG. 1 is a first perspective view of a tape dispenser;
FIG. 2 is front elevation view of the tape dispenser shown in FIG. 1

FIG. 3 is a rear elevation view of the tape dispenser shown in FIG. 1;

FIG. 4 is a left side view of the tape dispenser shown in FIG. 1;

FIG. 5 is a right side view of the tape dispenser shown in FIG. 1;

FIG. 6 is a top view of the tape dispenser of FIG. 1; and,

FIG. 7 is a bottom view of the tape dispenser of FIG. 1.

The broken lines shown in the drawings represent portions

of a tape dispenser that form no part of the claimed design.

1 Claim, 7 Drawing Sheets
